UNITED STATES PATENT OFFICE.

GEORGE F. PRENDERGAST, OF NEW YORK, N. Y., ASSIGNOR TO LENA M. PRENDERGAST, OF SAME PLACE.

DESIGN FOR A CIGAR AND ASH HOLDER.

SPECIFICATION forming part of Design No. 30,605, dated April 25, 1899.

Application filed April 18, 1896. Serial No. 588,186. Term of patent 14 years.

To all whom it may concern:

Be it known that I, GEORGE F. PRENDERGAST, a citizen of the United States, residing in the city, county, and State of New York, 5 have invented and produced a certain new and original Design for Cigar and Ash Holders and the Like, of which the following is a specification.

The new design relates to the shape of cigar and ash holders.

The new design is shown in the accompanying drawings, in which—

Figure 1 is a perspective view of a cigar and ash holder having the new design, and 5 Fig. 2 is top view thereof.

The distinctive features of the new design are an oblong tapering concave part A, having concave curves *a* in its edges, convex curves *b* at sides thereof, a trough-shaped interior *c*, a convex exterior *e*, a reduced or rounded end *f* at one end, and a cup-shaped substantially circular part B at the other end of the part A, having a cavity or hollow *g* on its upper side, curved outer wall *h*, and round

bottom *i*. The concave part *c* is a continuation of the cavity *g*. The part A is radial of the part B. The part B has an upper edge *j*. The convex wall *e* of the part A merges into the round wall *h* of the part B with a curve *k*, and the cavities *c* and *g* meet in a sharp 30 curve or corner *l*. Beneath the part B is a part C, of oblong shape, having a rectangular end *m* under the part A and a curved end *n* under the part B. Between the parts B and C is a rectangular part D, and on the part C 35 is an elongated part E.

What I claim is—

The design for a cigar and ash holder, substantially as herein described and shown in the drawings.

In witness whereof I have hereunto signed my name in the presence of two subscribing witnesses.

GEORGE F. PRENDERGAST.

Witnesses:

GEORGE H. FRASER,
THOMAS F. WALLACE.
